(57) **ABSTRACT**

An exemplary method relates to retrofitting a toilet comprising a base portion having a recessed rear portion and a front portion including a first side surface and a second side surface opposite the first side surface. The method generally includes adhering a first end of a skirt to the first side surface, wrapping the skirt around the recessed rear portion such that the recessed rear portion is covered by the skirt, and adhering a second end of the skirt to the second side surface.

TOILET SKIRT

**CROSS-REFERENCE TO RELATED
APPLICATIONS**

The present application claims the benefit of U.S. Provisional Patent Application No. 62/900,819, filed Sep. 16, 2019, the contents of which are incorporated by reference in their entirety.

TECHNICAL FIELD

The present disclosure generally relates to toilets, and more particularly but not exclusively relates to skirts for toilets.

BACKGROUND

The rear sides of toilets are typically difficult to reach for cleaning purposes, and often include crevices that accumulate dirt and grime. While certain commercially-available toilets are skirted to eliminate these crevices and facilitate cleaning, these toilets are often significantly more expensive than their non-skirted counterparts. Additionally, these skirted toilets require that an entirely new toilet be purchased and installed, and cannot be used to retrofit an existing installation. For these reasons among others, there remains a need for further improvements in this technological field.

SUMMARY

An exemplary method relates to retrofitting a toilet comprising a base portion having a recessed rear portion and a front portion including a first side surface and a second side surface opposite the first side surface. The method generally includes adhering a first end of a skirt to the first side surface, wrapping the skirt around the recessed rear portion such that the recessed rear portion is covered by the skirt, and adhering a second end of the skirt to the second side surface. Further embodiments, forms, features, and aspects of the present application shall become apparent from the description and figures provided herewith.

BRIEF DESCRIPTION OF THE FIGURES

FIG. 1 is a perspective view of a toilet that may be utilized in connection with certain embodiments.

FIG. 2 is a front view of the toilet illustrated in FIG. 1.

FIG. 3 is a side view of a toilet assembly that includes the toilet and a skirt according to certain embodiments.

FIG. 4 is a plan view of a skirt according to certain embodiments.

FIG. 5 is a plan view of a skirt according to certain embodiments.

FIG. 6 is a schematic flow diagram of a process according to certain embodiments.

**DETAILED DESCRIPTION OF ILLUSTRATIVE
EMBODIMENTS**

Although the concepts of the present disclosure are susceptible to various modifications and alternative forms, specific embodiments have been shown by way of example in the drawings and will be described herein in detail. It should be understood, however, that there is no intent to limit the concepts of the present disclosure to the particular

forms disclosed, but on the contrary, the intention is to cover all modifications, equivalents, and alternatives consistent with the present disclosure and the appended claims.

References in the specification to "one embodiment," "an embodiment," "an illustrative embodiment," etc., indicate that the embodiment described may include a particular feature, structure, or characteristic, but every embodiment may or may not necessarily include that particular feature, structure, or characteristic. Moreover, such phrases are not necessarily referring to the same embodiment. It should further be appreciated that although reference to a "preferred" component or feature may indicate the desirability of a particular component or feature with respect to an embodiment, the disclosure is not so limiting with respect to other embodiments, which may omit such a component or feature. Further, when a particular feature, structure, or characteristic is described in connection with an embodiment, it is submitted that it is within the knowledge of one skilled in the art to implement such feature, structure, or characteristic in connection with other embodiments whether or not explicitly described.

Additionally, it should be appreciated that items included in a list in the form of "at least one of A, B, and C" can mean (A); (B); (C); (A and B); (B and C); (A and C); or (A, B, and C). Similarly, items listed in the form of "at least one of A, B, or C" can mean (A); (B); (C); (A and B); (B and C); (A and C); or (A, B, and C). Items listed in the form of "A, B, and/or C" can also mean (A); (B); (C); (A and B); (B and C); (A and C); or (A, B, and C). Further, with respect to the claims, the use of words and phrases such as "a," "an," "at least one," and/or "at least one portion" should not be interpreted so as to be limiting to only one such element unless specifically stated to the contrary, and the use of phrases such as "at least a portion" and/or "a portion" should be interpreted as encompassing both embodiments including only a portion of such element and embodiments including the entirety of such element unless specifically stated to the contrary.

In the drawings, some structural or method features may be shown in certain specific arrangements and/or orderings. However, it should be appreciated that such specific arrangements and/or orderings may not necessarily be required. Rather, in some embodiments, such features may be arranged in a different manner and/or order than shown in the illustrative figures unless indicated to the contrary. Additionally, the inclusion of a structural or method feature in a particular figure is not meant to imply that such feature is required in all embodiments and, in some embodiments, may be omitted or may be combined with other features.

With reference to FIGS. 1 and 2, illustrated therein is a toilet 100 that may be utilized in connection with certain embodiments. The toilet 100 includes a base portion 110, a tank 120 mounted to the base portion 110, and a lid 130. The base portion 110 includes a recessed rear portion 112, a bowl 114, and a front portion 116 having a first side surface 117 and an opposite second side surface 118. As is typical, the rear portion 112 extends from the front portion 116 toward a wall 90. The toilet 100 is a conventional toilet, and may be of any type known in the art. As such, the toilet 100 need not be described in further detail herein.

With additional reference to FIG. 3, illustrated therein is a toilet assembly 200 according to certain embodiments. The toilet assembly 200 generally includes the toilet 100 and a toilet skirt 210 according to certain embodiments. The toilet skirt 210 is mounted to the base portion 110 of the toilet 100, and wraps around the rear side of the toilet 100 and covers the recessed rear portion 112. In the illustrated form, the skirt

210 includes a pair of curved cutouts **212**, each of which accommodates a corresponding and respective portion of the bowl **114**. In other embodiments, the cutouts **212** may be tapered or straight. Additionally or alternatively, a portion of the skirt **210** may be feathered to fit the bowl **114**.

With additional reference to FIG. 4, illustrated therein is a skirt **300**, which is one example of the skirt **210**. The skirt **300** generally includes a base panel **310**, a first side panel **320** extending from a first side of the base panel **310**, and a second side panel **330** extending from the opposite second side of the base panel **310**. The skirt **210** may be formed of a rigid or semi-rigid material such that the skirt **210** at least partially retains its shape when installed to the toilet **100**. While other materials and forms are contemplated, in the illustrated embodiment, the skirt **300** is formed of a plastic sheet.

The base panel **310** includes an upper edge **312**, a lower edge **314**, a first side **316** extending between the upper edge **312** and the lower edge **314**, and an opposite second side **318** extending between the upper edge **312** and the lower edge **314**. In certain forms, the first side **316** may be defined by a crease **315** or radius and/or the second side **318** may be defined by a crease **317** or radius. Creases **315**, **317** may, for example, be provided in the form of an indented line and/or a line of perforations. In certain forms, such creases **315**, **317** may be omitted. In certain forms, the base panel **310** further includes a center cutout **319** sized and shaped to accommodate a portion of the rear portion **112**.

The first side panel **320** extends from the first side **316** of the base panel **310** to a first end **322** of the skirt **300**. The first end **322** may have positioned thereon a first releasable securing means such as a first adhesive region **324**, which may be covered by a removable protective film **325**. It is also contemplated that the first securing means may be provided in another form, such as one that includes a hook-and-loop fastener strip, a hook-hoop fastener strip, and/or one or more suction cups. The first side panel **320** may further include a cutout **326** sized and shaped to accommodate a portion of the bowl **114**. The cutout **326** may have a curved edge **327** that generally conforms to the curved line defining the intersection of the bowl **114** and the first side surface **117**. It is also contemplated that the edge **327** may be tapered or straight to define the cutout **326** as a tapered or straight cutout.

In the illustrated form, the second side panel **330** is a mirror image of the first side panel **320**, and extends from the second side **318** of the base panel **310** to a second end **332** of the skirt **300**. It is also contemplated that the second side panel **330** may not necessarily be a mirror image of the first side panel **320**. The second end **332** may have positioned thereon a second releasable securing means such as a second adhesive region **334**, which may be covered by a removable protective film **335**. It is also contemplated that the second securing means may be provided in another form, such as one that includes a hook-and-loop fastener strip, a hook-hoop fastener strip, and/or one or more suction cups. The second side panel **330** may further include a cutout **336** sized and shaped to accommodate a portion of the bowl **114**. The cutout **336** may have a curved edge **337** that generally conforms to the curved line defining the intersection of the bowl **114** and the second side surface **118**. It is also contemplated that the edge **337** may be tapered or straight to define the cutout **336** as a tapered or straight cutout.

With additional reference to FIG. 5, illustrated therein is a skirt **400**, which is another example of the skirt **210**. The skirt **400** generally includes a base panel **410**, a first side panel **420** extending from a first side of the base panel **410**, and a second side panel **430** extending from the opposite

second side of the base panel **410**. While other materials and forms are contemplated, in the illustrated embodiment, the skirt **400** is formed of a plastic sheet.

The base panel **410** includes an upper edge **412**, a lower edge **414**, a first side **416** extending between the upper edge **412** and the lower edge **414**, and an opposite second side **418** extending between the upper edge **412** and the lower edge **414**. In certain forms, the first side **416** may be defined by a crease **415** and/or the second side **418** may be defined by a crease **417**. Creases **415**, **417** may, for example, be provided in the form of an indented line and/or a line of perforations. In certain forms, such creases **415**, **417** may be omitted. In certain forms, the base panel **410** further includes a center cutout **419** sized and shaped to accommodate a portion of the rear portion **112**.

The first side panel **420** extends from the first side **416** of the base panel **410** to a first end **422** of the skirt **400**. The first end **422** may have positioned thereon a first releasable securing means such as a first adhesive region **424**, which may be covered by a removable protective film **425**. It is also contemplated that the first securing means may be provided in another form, such as one that includes a hook-and-loop fastener strip, a hook-hoop fastener strip, and/or one or more suction cups. The first side panel **420** may further include a cutout **426** sized and shaped to accommodate a portion of the bowl **114**. The cutout **426** may have a curved edge **427** that generally conforms to the curved line defining the intersection of the bowl **114** and the first side surface **117**. It is also contemplated that the edge **427** may be tapered or straight to define the cutout **426** as a tapered or straight cutout.

In the illustrated form, the second side panel **430** is a mirror image of the first side panel **420**, and extends from the second side **418** of the base panel **410** to a second end **432** of the skirt **400**. It is also contemplated that the second side panel **430** may not necessarily be a mirror image of the first side panel **420**. The second end **432** may have positioned thereon a second releasable securing means such as a second adhesive region **434**, which may be covered by a removable protective film **435**. It is also contemplated that the second securing means may be provided in another form, such as one that includes a hook-and-loop fastener strip, a hook-hoop fastener strip, and/or one or more suction cups. The second side panel **430** may further include a cutout **436** sized and shaped to accommodate a portion of the bowl **114**. The cutout **436** may have a curved edge **437** that generally conforms to the curved line defining the intersection of the bowl **114** and the second side surface **118**. It is also contemplated that the edge **437** may be tapered or straight to define the cutout **436** as a tapered or straight cutout.

While other geometries are contemplated, in the illustrated form, the base panel **410** is substantially trapezoidal. The upper edge **412** has a first length dimension **d412**, and the lower edge **414** has a second length dimension **d414** greater than the first length dimension **d412**. Additionally, when the skirt **400** is laid flat, lower edges **429**, **439** of the side panels **420**, **430** define oblique angles **θ429**, **θ439** relative to the lower edge **414** of the base panel **410**. This arrangement may aid in conforming the skirt **400** to the geometries of certain forms of the toilet **100**.

Certain embodiments of the present disclosure relate to methods of retrofitting an existing toilet **100** with a skirt **210** in order to provide a toilet assembly **200**. While an example method will now be described with specific reference to the skirt **300** illustrated in FIG. 4, it is to be appreciated that the method may alternatively be performed with the skirt **400** illustrated in FIG. 5 or other skirts having similar features.

5

With additional reference to FIG. 6, illustrated therein is a process **500** according to certain embodiments. Blocks illustrated for the process **500** are understood to be examples only, and blocks may be combined or divided, and added or removed, as well as re-ordered in whole or in part, unless explicitly stated to the contrary. Additionally, while the blocks are illustrated in a relatively serial fashion, it is to be understood that two or more of the blocks may be performed concurrently or in parallel with one another.

The process **500** may include block **510**, which generally involves applying bends to the skirt **300**. Block **510** may, for example, involve applying the bends along the creases **315**, **317** to define the first and second sides **316**, **318** of the base panel **310**. In other forms, block **510** may be omitted. For example, the process **500** may instead involve applying the skirt **300** to the toilet **100** in a continuously-curved form.

The process **500** includes block **520**, which generally involves releasably securing the first end **322** of the skirt **300** to the first side surface **117** of the toilet base portion **110** using the first releasable securing means. Block **520** may involve positioning the first side panel **320** such that a portion of the bowl **114** is accommodated in the first cutout **326**, and releasably securing the first end **322** to the first side surface **117** with the bowl **114** accommodated in the first cutout **326**. In certain embodiments, such as those in which the first releasable securing means comprises one or more suction cups, block **520** may involve applying the suction cups to the first side surface **117** to releasably secure the first end **322** to the first side surface **117**.

In certain embodiments, block **520** may involve adhering the first end **322** to the first side surface **117** using the first adhesive region **324**. In certain embodiments, block **520** may involve removing the protective film **325** to expose the first adhesive region **324**, and adhering the first end **322** of the skirt **300** to the first side surface **117** using the first adhesive region **324**. In other forms, such as those in which the skirt **300** does not include the adhesive region **324**, block **520** may involve adhering the first end **322** of the skirt **300** to the first side surface **117** using a separate adhesive, such as tape or glue.

In certain embodiments, the first releasable securing means may comprise a hook-and-loop fastener mechanism including a first strip (e.g. one of a hook strip or a loop strip) adhered to the first end **322** and a second strip (e.g., the other of a hook strip or a loop strip) having an adhesive side. In such forms, block **520** may involve applying the second strip to the first side surface **117** using the adhesive side such that the hooks or loops are exposed, and engaging the first strip with the second strip to releasably secure the first end **322** to the first side surface **117**. Similar acts may be performed in embodiments in which the first releasable securing means comprises a hook-hook fastener mechanism.

The process **500** also includes block **530**, which generally involves wrapping the skirt **300** around the back of the base portion **110** to cover the recessed rear portion **112**. In certain embodiments, such as those in which the base panel **310** includes the center cutout **319**, block **530** may involve positioning a portion of the rear portion **112** in the center cutout **319**.

The process **500** includes block **540**, which generally involves releasably securing the second end **332** of the skirt **300** to the second side surface **118** of the toilet base portion **110** using the second releasable securing means. Block **540** may involve positioning the second side panel **330** such that a portion of the bowl **114** is accommodated in the second cutout **336**, and releasably securing the second end **332** to the second side surface **118** with the bowl **114** accommo-

6

dated in the second cutout **336**. In certain embodiments, such as those in which the second releasable securing means comprises one or more suction cups, block **540** may involve applying the suction cups to the second side surface **118** to releasably secure the second end **332** to the second side surface **118**.

In certain embodiments, block **540** may involve adhering the second end **332** to the second side surface **118** using the second adhesive region **334**. In certain embodiments, block **540** may involve removing the protective film **335** to expose the first adhesive region **334**, and adhering the second end **332** of the skirt **300** to the second side surface **118** using the first adhesive region **334**. In other forms, such as those in which the skirt **300** does not include the adhesive region **334**, block **540** may involve adhering the second end **332** of the skirt **300** to the second side surface **118** using a separate adhesive, such as tape or glue.

In certain embodiments, the second releasable securing means may comprise a hook-and-loop fastener mechanism including a first strip (e.g. one of a hook strip or a loop strip) adhered to the second end **332** and a second strip (e.g., the other of a hook strip or a loop strip) having an adhesive side. In such forms, block **540** may involve applying the second strip to the second side surface **118** using the adhesive side such that the hooks or loops are exposed, and engaging the first strip with the second strip to releasably secure the second end **332** to the second side surface **118**. Similar acts may be performed in embodiments in which the second releasable securing means comprises a hook-hook fastener mechanism.

With the process **500** completed, the conventional toilet **100** has been retrofitted with the skirt **210** (e.g., the skirt **300** or the skirt **400**) to form the toilet assembly **200**. In this state, the skirt **210** covers the recessed rear portion **112**, thereby giving the appearance of a skirted toilet at significantly lower cost. The color of the skirt **210** may be selected to match the color of the toilet **100** to further enhance this appearance. The skirt **210** also aids in reducing the build-up of dust and grime in the recessed rear portion **112**, and may provide a smooth surface that is more easily cleaned than the contoured and recessed rear portion **112** of the toilet **100**. When the skirt **210** becomes dirty, the skirt **210** may be removed for cleaning or discarded. In certain forms, the adhesive regions are provided as releasable adhesive regions that facilitate the removal of the skirt **210**. Additionally or alternatively, the adhesive regions may be provided as reusable or replaceable adhesive regions that facilitate the use of the same skirt **210** multiple times.

As noted above, the skirt **210** may be formed of a flat plastic sheet. Such a plastic sheet may have a sufficient flexibility to allow the skirt **210** to be bent or curved into its final shape, while having sufficient rigidity to maintain such a shape under light cleaning (e.g. wiping and/or dusting). In certain forms (including but not limited to those in which the skirt **210** is provided with creases), the skirt **210** may be bent into an H shape, while in other embodiments, the skirt **210** may be curved into a C shape.

While the invention has been illustrated and described in detail in the drawings and foregoing description, the same is to be considered as illustrative and not restrictive in character, it being understood that only the preferred embodiments have been shown and described and that all changes and modifications that come within the spirit of the inventions are desired to be protected. It should be understood that while the use of words such as preferable, preferably, preferred or more preferred utilized in the description above indicate that the feature so described may be more desirable,

it nonetheless may not be necessary and embodiments lacking the same may be contemplated as within the scope of the invention, the scope being defined by the claims that follow. In reading the claims, it is intended that when words such as "a," "an," "at least one," or "at least one portion" are used there is no intention to limit the claim to only one item unless specifically stated to the contrary in the claim. When the language "at least a portion" and/or "a portion" is used the item can include a portion and/or the entire item unless specifically stated to the contrary.

5 10 15

What is claimed is:

1. A method of retrofitting a toilet comprising a base portion having a recessed rear portion and a front portion including a first side surface and a second side surface opposite the first side surface, the method comprising:
providing a skirt, the skirt comprising:
a base panel having an upper edge, a lower edge, a first side extending between the upper edge and the lower edge, and a second side extending between the upper edge and the lower edge;
a first side panel extending from the first side of the base panel, the first side panel comprising a first cutout sized and shaped to accommodate a first portion of the bowl, and first releasable securing means positioned near a first end of the first side panel, wherein the first end of the first side panel is opposite the first side of the base panel; and
a second side panel extending from the second side of the base panel, the second side panel comprising a second cutout sized and shaped to accommodate a second portion of the bowl, and second releasable securing means positioned near a second end of the second side panel, wherein the second end of the second side panel is opposite the second side of the base panel;
releasably securing the first end of the first side panel of the skirt to the first side surface;
wrapping the skirt around the recessed rear portion such that the recessed rear portion is covered by the skirt; and
releasably securing the second end of the second side panel of the skirt to the second side surface.
2. The method of claim 1, further comprising accommodating the first portion of the bowl in the first cutout; and accommodating the second portion of the bowl in the second cutout.
3. The method of claim 1, wherein releasably securing the first end of the skirt to the first side surface comprises adhering the first end of the skirt to the first side surface; and wherein releasably securing the second end of the skirt to the second side surface comprises adhering the second end of the skirt to the second side surface.
4. The method of claim 3, further comprising:
removing a first protective film from the first end of the first side panel of the skirt to expose a first adhesive region, wherein releasably securing the first end of the skirt to the first side surface comprises adhering the first end of the skirt to the first side surface via the first adhesive region; and
removing a second protective film from the second end of the second side panel of the skirt to expose a second adhesive region, wherein adhering the second end of the skirt to the second side surface comprises adhering the second end of the skirt to the second side surface via the second adhesive region.

35 40 45 50

5. A toilet assembly, comprising:
a toilet comprising a base portion, the base portion including a recessed rear portion, a bowl, and a front portion, the front portion including a first side surface and a second side surface opposite the first side surface; and
a skirt, the skirt comprising:
a base panel having an upper edge, a lower edge, a first side extending between the upper edge and the lower edge, and a second side extending between the upper edge and the lower edge;
a first side panel extending from the first side of the base panel, the first side panel comprising a first cutout sized and shaped to accommodate a first portion of the bowl, and first releasable securing means positioned near a first end of the first side panel, wherein the first end of the first side panel is opposite the first side of the base panel; and
a second side panel extending from the second side of the base panel, the second side panel comprising a second cutout sized and shaped to accommodate a second portion of the bowl, and second releasable securing means positioned near a second end of the second side panel, wherein the second end of the second side panel is opposite the second side of the base panel;
wherein the skirt covers the recessed rear portion, wherein the first end of the first side panel is releasably secured to the first side surface, and wherein the second end of the second side panel is releasably secured to the second side surface.
6. The toilet assembly of claim 5, wherein the upper edge has a first length, and wherein the lower edge has a second length greater than the first length.
7. The toilet assembly of claim 6, wherein the base panel is trapezoidal.
8. The toilet assembly of claim 5, wherein the base panel comprises a further cutout through which a portion of the rear portion extends.
9. The toilet assembly of claim 5, wherein the first end of the first side panel comprises a first adhesive region by which the first end is adhered to the first side surface; and wherein the second end of the second side panel comprises a second adhesive region by which the second end is adhered to the second side surface.
10. A skirt for a toilet comprising a bowl, the skirt comprising:
a base panel having an upper edge, a lower edge, a first side extending between the upper edge and the lower edge, and a second side extending between the upper edge and the lower edge;
a first side panel extending from the first side of the base panel, the first side panel comprising:
a first curved cutout sized and shaped to accommodate a first portion of the bowl; and
first releasable securing means positioned near a first end of the first side panel,
wherein the first end of the first side panel is opposite the first side of the base panel; and
a second side panel extending from the second side of the base panel, the second side panel comprising:
a second curved cutout sized and shaped to accommodate a second portion of the bowl; and
second releasable securing means positioned near a second end of the second side panel, wherein the second end of the second side panel is opposite the second side of the base panel;
wherein the skirt is operable to be laid flat.

11. The skirt of claim **10**, wherein the first securing means comprises a first adhesive region, and wherein the second releasable securing means comprises a second adhesive region.

12. The skirt of claim **11**, further comprising a first ⁵ removable film covering the first adhesive region, and a second removable film covering the second adhesive region.

13. The skirt of claim **10**, wherein the lower edge is longer than the upper edge such that the base panel is trapezoidal.

14. The skirt of claim **10**, wherein each of the first side ¹⁰ panel and the second side panel comprises a corresponding and respective lower edge that extends at an oblique angle relative to the lower edge of the base panel when the skirt is laid flat.

15. The skirt of claim **10**, wherein the skirt is formed of ¹⁵ a plastic sheet.

16. The skirt of claim **10**, wherein each of the first side and the second side is defined by a corresponding and respective crease.

17. The skirt of claim **16**, wherein each crease comprises ²⁰ at least one of an indented line, a line of perforations, or a formed radius.
